ATTORNEY

UNITED STATES PATENT OFFICE.

CHARLES E. WILLEY, OF LOUISVILLE, KENTUCKY.

ELECTRIC-GENERATOR BRUSH-HOLDER.

1,392,996.

Specification of Letters Patent. Patented Oct. 11, 1921.

Application filed May 27, 1921. Serial No. 473,219.

To all whom it may concern:

Be it known that I, CHARLES E. WILLEY, a citizen of the United States of America, residing at Louisville, in the county of Jefferson and State of Kentucky, have invented 5 certain new and useful Improvements in Electric-Generator Brush-Holders, of which the following is a specification.

This invention relates to electric generators and motors and has special reference to 10 a brush holder for devices of this description.

One important object of the invention is to improve the general construction of such 15 brush holders.

A second important object of the invention is to provide an improved spring arrangement for forcing the brush held by the holder, against the commutator or ring of a 20 dynamo electric machine.

A third important object of the invention is to provide an improved construction of brush holder wherein the friction due to the tension spring bearing on the brush 25 holder arm as in the ordinary construction, will be eliminated.

A fourth important object of the invention is to provide an improved construction of brush holder so arranged as to more effectively utilize the resiliency of a brush holder 30 spring as well as to increase the life thereof.

With the above and other objects in view, the invention consists in general of certain novel details of construction and combinations 35 of parts hereinafter fully described, illustrated in the accompanying drawings, and specifically claimed.

In the accompanying drawings, like characters of reference indicate like parts in the 40 several views, and:—

Figure 1 is a side elevation of a brush holder constructed in accordance with this invention.

Fig. 2 is a plan view thereof, the view 45 showing a portion of the stud on the dynamo electric machine which is employed in mounting the brush holder.

Fig. 3 is an end view of the brush holder.

Fig. 4 is a plan view of the improved 50 spring removed from the holder.

Fig. 5 is an end view of said spring.

Fig. 6 is an elevation showing a certain link employed in connection with this brush 55 holder.

Fig. 7 is an edge view of said link.

In the embodiment of the invention here-

in illustrated there is provided a brush holder arm having a body portion 10 preferably made in the shape of a tapered I-beam. At one end the arm 10 is bifurcated 60 as at 11 and each arm of the bifurcation forms a bearing ring 12, which rings are of such sizes as to rotatably fit on the stud S of a dynamo electric machine. At the other end of the arm 10 there is provided a flat 65 head 13 considerably broader than the arm and this end of the arm also has on its upper side a boss 14 having a flat surface substantially at right angles to the face of the head 13. In the upper face of the boss is provided 70 a notch 15. At B is shown the ordinary brush and this brush sits against the flat face of the head 13 and is held in position on that face by a clamp spring having a straight portion 16 secured on the boss 14 by screws 17. 75 This straight portion 16 extends over the brush B and is then bowed as at 18 and extends downward along the outer side of the brush as at 19 so that the brush is clamped by the portion 19 against the head 13. 80

Between the rings 12 there is mounted on the stud S a clamp ring having a body 20. This ring is split and at each side of the split portion is a lug 21, one of said lugs being threaded so that a shoulder screw 22 85 may be passed through the other lug and screwed into the threaded lug to draw the lugs together and thus clamp the ring firmly on the stud S. It will be seen that when this ring is clamped on the stud the arm 10 90 is free to rise and fall but not move laterally.

Extending up from the ring 20 is a boss 23 having a flat upper surface to support the fixed end of a leaf spring 24, said fixed end being held to the boss 23 by screws 25. This 95 spring 24 extends through an opening 26 in a link 27, the opening 26 being located at the upper end of said link. The portion 16 of the brush clamp spring passes through a lower opening 28 formed in said link so as 100 to hold the lower end of the link in the notch 15 and the proportions of these parts are such that the spring 24 has its free end raised by the link 27 so that the brush B is constantly urged downward. 105

In order to provide an electrical connection for the brush B a flat woven conductor 29 is secured beneath the spring 24 by the screws 17 and 25 as clearly shown in Fig. 1.

In assembling the device the clamp ring 110 20 is placed between the rings 12 with the screw 22 loosened. The three rings are then

slipped over at the stud S to the proper portion lengthwise of the stud. The clamp ring 20 is then rotated until the spring 24 presses on the link 27 with the proper force 5 to hold the brush B in position. The screw 22 is then tightened and the clamp ring 20 locked in this position.

With the construction it will be seen that the spring 24 is entirely free from the arm 10 and only acts on said arm through the link 27. Thus, since the link can tilt slightly there is practically no rubbing friction on the spring due to oscillations of the arm 10 and, this friction being eliminated 15 and the spring 24 free throughout its length, the full resiliency of the spring becomes effective on the brush. Furthermore wear of the spring due to rubbing is eliminated and consequently the life of 20 the spring is prolonged.

There has thus been provided a simple and efficient device of the kind described and for the purpose specified.

It is obvious that minor changes may be 25 made in the form and construction of the invention without departing from the material principles thereof. It is not therefore desired to confine the invention to the exact form herewith shown and described, but it 30 is wished to include all such as properly come within the scope claimed.

Having thus described the invention, what is claimed as new, is:—

1. In a brush holder of the class described, an arm arranged for pivotal mounting on a stud, a brush clamp at the free end of said arm, a clamp ring engageable on the stud, a leaf spring having one end fixed to said ring, and means loosely connecting the 40 other end of said spring and the arm adjacent its free end.

2. In a brush holder of the class described, an arm arranged for pivotal mounting on a stud, a brush clamp at the free end of said 45 arm, a clamp ring engageable immovably in fixed position on the stud, a leaf spring hav-

ing one end fixed to the ring and projecting longitudinally over the arm, and a link connecting the free ends of said arm and spring.

3. In a brush holder of the class described, 50 an arm arranged for pivotal mounting on a stud, a brush clamp at the free end of said arm, a clamp ring engageable immovably in fixed position on the stud, a leaf spring having one end fixed to the ring and projecting longitudinally over the arm, and a link having its lower end loosely resting on the arm and provided adjacent its upper end with a slot wherethrough the free end of the spring passes. 60

4. In a brush holder of the class described, an arm arranged for pivotal mounting on a stud, a brush holder at the free end of said arm including a clamping spring having one end secured to the arm, an upstanding link 65 at the free end of said arm having a slot adjacent each end, the fixed end of the spring passing through the lower of said slots, a clamp ring arranged for fixed mounting on the stud, and a spring having 70 one end fixed to the clamp ring and the other end passing through the upper of the link slots.

5. In a brush holder of the class described, an arm bifurcated at one end and having 75 the bifurcation in the form of journal rings adapted to fit revolvably on a stud, a clamp ring between the journal rings and having means to clamp the same in fixed position on the stud, a head on said arm, a clamp 80 spring arranged to coöperate with said head and hold a brush, said clamp spring having one end fixedly secured to the arm, a link having a slot adjacent each end, the fixed end of said spring extending through the 85 lower slot, an upstanding boss on said clamp ring, and a leaf spring having one end fixed to the boss and the other end extending through the upper link slot.

In testimony whereof I affix my signature. 90

CHARLES E. WILLEY.
